UNITED STATES PATENT OFFICE.

LEID P. DERR, OF PITTSBURGH, PENNSYLVANIA.

FIELD-COVER.

1,088,407.

Specification of Letters Patent. Patented Feb. 24, 1914.

Application filed February 26, 1913. Serial No. 750,734.

To all whom it may concern:

Be it known that I, LEID P. DERR, a citizen of the United States, and residing in the city of Pittsburgh, in the county of Allegheny and State of Pennsylvania, have invented or discovered new and useful Improvements in Field-Covers, of which the following is a specification.

My invention consists in new and useful improvements in covers for playing fields, such as baseball diamonds, and in means for stretching and removing the same. The purpose of such covers is to protect the field from wet and maintain it in a sufficiently dry condition for use.

My object is to provide efficient and expeditious means for stretching the cover over the field, for removing the same when the field is to be used, and for storing the cover out of the way when not in use.

For these purposes I provide a cover of canvas or other suitable flexible material mounted on a roller which is preferably ventilated, as for instance formed of slats, to enable a damp cover to dry out when rolled up. Power actuated means are provided for rolling up and unrolling the cover. Drums are provided, operated with the roller, upon which are mounted pull ropes which unwind as the cover rolls up and vice versa, said pull ropes being carried under the field to the other side thereof and thence over pulleys and across the field to be attached to the loose edge of the cover. Thus the pull ropes serve to draw and stretch the cover across the field when the cover is unwound and to guide and control the winding up of the cover. The ropes are detachable from the cover so as to be removed from the playing surface when the cover is rolled up.

I mount the roller in such a manner that it may be lowered out of the way into a pit when the cover is rolled up thereon and may be elevated out of such pit when the cover is to be stretched over the field. I provide a pivoted lid for such pit which automatically raises when the roller is elevated, and closes, concealing said pit, when the roller is lowered.

The pulleys on the opposite side of the field, over which the pull ropes pass, are mounted in swinging brackets set in a pit, so that when the ropes are detached from the

cover, said brackets may be swung down out 55 of the way in said pit. Said last named pit is also provided with a lid automatically controlled in unison with the lid of the first named pit so that said pit is covered and concealed when the canvas cover is not in 60 use. Said lids are preferably provided with anti-slipping top surface to prevent accidents to players.

Novel means are provided for raising and lowering the roller, for opening and shutting the pit lids, and for winding and unwinding the cover and the pull ropes. Other novel features of construction and arrangement of parts will appear from the following description.

In the accompanying drawings, Figure 1 is a plan view of a baseball diamond fitted with my invention, the pit lids being shown open in dotted lines, the roller and pull rope pulleys being shown raised and the 75 canvas cover stretched over the diamond; the permanent covering being broken away for the sake of clearness. Fig. 2 is an enlarged broken vertical section of the same, showing the roller and pull rope pulleys 80 raised, the cover unwound and stretched across the diamond and the pull ropes attached to the edge of the cover; Fig. 3 is an end view of the roller dismounted; Fig. 4 is a broken side elevation of the same; Fig. 5 85 is an enlarged perspective of one of the pull rope pulleys and its mounting; Fig. 6 is an enlarged detail elevation of one of the brackets by means of which the roller is mounted; Fig. 7 is a similar view showing a slight 90 modification of the same, and Fig. 8 is a detail in vertical section, similar to Fig. 2, but showing one of the pull rope pulley brackets folded down into its pit and the lid of said pit closed.

The following is a detailed description of the drawings:

A represents a baseball diamond or other playing field. B is an open trench or pit extending along one side thereof and preferably suitably lined with concrete.

C is a permanently closed or covered pit preferably lined with concrete and adjacent to pit B, whose top may be sodded or otherwise covered to correspond to the surface of 105 the playing field.

D is a lid adapted to close the pit B and pivoted at the edge of said pit away from

diamond A. Said lid D is provided with a surface, 1, of an anti-slipping character to prevent accidents to players. Said lid may be conveniently pivoted by means of a shaft 2 journaled in brackets 3 attached to the wall of pit B. At one end said lid is provided with a rearwardly extending arm 4, the purpose of which will be explained.

5 represents a pair of guide posts fixed 10 vertically in the pit B adjacent to the front wall of said pit and at either end thereof. E and E' represent a pair of brackets mounted to slide vertically on said posts 5. 6 represents a pair of rotary worms vertically 15 mounted in said pit B and engaging threaded vertical bores in the brackets E and E', whereby when said worms are rotated said brackets ascend or descend on the posts 5 according to the direction of the rotation of 20 the worms.

The brackets E and E' are provided with journal boxes 8 in which are journaled the ends of axial shaft 9 upon which the roller F is rigidly mounted. The roller F is preferably composed of an annular series of 25 slats 10 so that when the canvas cover, marked G, is wound upon the same in a wet condition, the latter may readily dry out without rotting. The ends of the roller F 30 are provided with rope drums 11.

One end of shaft 9, the end journaled in bracket E, is provided with a rigidly mounted gear 12 which meshes with a gear 13 rigidly mounted on a spur shaft 14 journaled in the bracket E. 15 is a sprocket 35 also rigidly mounted on spur shaft 14 and preferably secured to the gear 13. A chain 16 operatively connects the sprocket 15 with a smaller sprocket 17 loosely mounted on a 40 shaft 18 journaled in two standards 19 extending from the bottom of the pit C.

20 is a gear loosely mounted and sliding on shaft 18, and meshing with a smaller gear 21 on the shaft 22 of the reversible motor H. 45 The hubs of sprockets 17 and 20 are arranged to interlock when said sprocket 20 is shifted, as by lever 23, into contact with sprocket 17. It is thus evident that the roller F may remain stationary or be rotated in either direction by the motor H, as 50 may be desired.

The worms 6 are provided at their lower ends with rigidly mounted beveled gear 24 which mesh with beveled gear 25 on the end 55 of a shaft 26 horizontally journaled in pillow blocks 27 on the bottom of pit B.

28 is a sprocket wheel rigidly mounted on shaft 26 and operatively connected by means of a chain 29 with a smaller sprocket 30 60 loosely mounted on the shaft 22 of motor H. 31 is a clutch member keyed to slide on said shaft 22 and controlled by a lever mechanism. 32. By means of said clutch the sprocket 30 65 may be made to rotate in either direction with the motor or remain idle. It is evident

that a rotation of the sprocket 30 in one direction would rotate the worms 6 in the proper direction to raise the brackets E and E' and with them the roller F, while the rotation of said sprocket 30 in the opposite direction would lower the roller F.

A rope or cable 33 is attached to the end of arm 4 of lid D and passing under the guide pulleys 34 and 35, extends up through the interior of the worm 6, which is made hollow and is attached to the upwardly extending standard 36 mounted on the bracket E. It is evident that as the roller F rises, the rope 33 will be drawn upwardly through the worm 6, drawing down on arm 4 and raising the lid D to permit the elevation of the roller F. Vice versa, the descent of roller F will slacken said rope 33 and permit said lid to close of its own weight.

1 is a pit, preferably lined with concrete, 85 along the side of the diamond A, opposite to pit B, and permanently covered and sodded above for the greater portion of its length. In one or more places, however, said permanent covering is omitted and a hinged 90 lid J substituted. In the drawings I have shown two of said lids which are rigidly mounted on a rock shaft 37 journaled in brackets 38 attached to the outer wall of pit I. Said shaft 37 is provided with a 95 rigid arm 39 to whose end is attached a rope or cable 40 which extends through a covered trench or buried pipe 41 under the diamond A and enters the pit B. Passing over pulleys 42, 43 and 44, said rope is attached to 100 the bracket E so that when the roller F rises, said lids J are opened contemporaneously with lid D and correspondingly closed when said roller descends.

45 are pulleys mounted in brackets 46 105 which are pivoted to swing on bases 47 mounted in the bottom of pit I. The brackets 46 may be either elevated, in Fig. 2 when the lids J are raised, or depressed into the pit when the lids are lowered, as 110 shown in Fig. 8.

K are pull ropes or cables wound about the drums 11 on the ends of roller F, the winding of said ropes being opposite to that of the canvas cover G. Said ropes extend through covered trenches or buried pipes 48 along the sides of diamond A and over pulleys 49 and 50 in the pit I. When the cover is rolled up, the ends of the ropes K may be coiled up in the pit I, as shown in 120 Fig. 8, but when said ropes are to be used, the ends of said ropes are led over the pulleys 45, the brackets 46 being elevated, as shown in Fig. 2, and led over the diamond A and attached by means of their hooks 51 125 to the eyelets 52 on the free edge of cover G.

It is evident that as the cover G is unwound, the pull ropes K are wound up, so that said ropes act to draw and stretch the cover over the surface of the diamond and 130

hold the same in its stretched and flattened position. Vice versa, as the cover is wound up on the roller F, the ropes K are unwound from the drums 11, thus slackening said ropes and permitting the cover to be withdrawn from the diamond, the pull ropes K acting as guides to assist in winding up the cover.

The operation of my device is as follows: Assuming that the cover G is rolled up on the roller F, the latter depressed in the pit B and the lids D and J closed, the clutch 31 is thrown to connect the sprocket 30 with the shaft 22 of motor H, thus rotating the worms 6 and raising the roller F, the lids 15 D and J automatically rising in unison with said operation. When the roller F has been raised out of pit B, the clutch 31 is thrown off, stopping the elevation of the roller. The ends of ropes K are now carried 20 over the pulleys 45 and across the diamond A and hooked into the eyelets 52 on the free edge of the cover G. The sprocket 20 is now thrown into engagement with the sprocket 17 by means of lever 23 and the 25 roller F and its drums 11 started to rotate in the direction required to unwind the cover G. As the cover G unwinds the pull ropes K are wound up on the drums 11, thus drawing the cover tautly over the 30 diamond A. When the cover has been unwound sufficiently to cover the diamond A, the sprocket 20 is shifted out of engagement with the sprocket 17, thus causing the roller F and drums 11 to remain stationary and 35 holding the cover snugly stretched over the diamond. When it is desired to remove the cover, the roller F and drums 11 are caused to rotate in the opposite direction, winding up the cover and unwinding the pull ropes 40 K, thus permitting the cover to be withdrawn across the diamond A and to be stored on the roller F. The ends of the pull ropes are then disengaged from the edge of the cover G and coiled up in the pit I and 45 the brackets 46 swung down into said pit, as shown in Fig. 8. The worms 6 are then rotated in the opposite direction to that described above, resulting in lowering the roller F and the cover down into the pit B 50 and closing the lids D and J.

As another method of raising and lowering the lid D, I may provide the brackets E and E', as shown in connection with bracket E' in Fig. 7, with cams 53 which contact 55 with the lid D and raise the same when the roller F is raised and permit said lid to descend and close when said roller is depressed.

I prefer to provide a pit for my cover roller and raise and lower the same therein 60 in substantially the manner described, but if desired, the roller may be mounted above ground in some protected spot, such as under the grandstand, in which case I may omit the mechanism for raising and lowering. 65 However, in such case my arrangement of

pull rope pulleys mounted on swinging supports contained in a pit provided with a cover will be found to be very useful.

What I desire to claim is:—

1. The combination of a field cover, a 70 roller upon which the same may be wound, drums rotating in unison with said roller, pull ropes wound on said drums in such a manner as to unwind while said cover is being rolled up and vice versa, said ropes 75 extending under the field to the opposite side thereof, the said opposite side of the field being provided with a pit, pulleys mounted in said pit and adapted to be raised out of the same when in use and to be concealed in the same when not in use over which said ropes may be passed to be attached to the free edge of the cover, whereby the rotation of the roller in one direction unrolls and stretches said cover over the 80 field while the opposite rotation of said roller withdraws said cover and rolls the same up on said roller, and a lid adapted to close said pit when said pulleys are not in use. 90

2. In combination with a playing field provided with a pit, a cover for said field, a roller for said cover mounted in said pit, means for raising said roller out of said pit when said cover is to be used, and means 95 for rotating said roller.

3. In combination with a playing field provided with a pit, a cover for said field, a roller for said cover mounted in said pit, means for raising said roller out of said 100 pit when said cover is to be used, means for rotating said roller, and a lid adapted to close said pit when said cover is not in use.

4. In combination with a playing field provided with a pit, a cover for said field, 105 a roller for said cover mounted in said pit, means for raising said roller out of said pit when said cover is to be used, means for rotating said roller, a lid adapted to close said pit and means whereby when said 110 roller is raised said lid is automatically opened and when said roller is lowered said lid is automatically closed.

5. In combination with a playing field provided with pits, a cover for said field, 115 a roller for said cover mounted in one of said pits, means for raising said roller out of said pit when said cover is to be used, means for rotating said roller, drums rotating in unison with said roller, pull ropes 120 wound on said drums in such a manner as to unwind while said cover is wound up and vice versa, said ropes extending under said field to a second pit, pulleys over which said ropes may be passed to be attached to 125 the free edge of said cover whereby the rotation of the roller in one direction unrolls and stretches said cover over the field while the opposite rotation of said roller withdraws said cover and rolls the same up on 130

4

said roller, extensible supports for said pulleys in said second pit whereby said pulleys may be sunk into said second pit when not in use, lids for said pits, and means whereby when said roller is raised said lids are automatically opened and when said roller is lowered said lids are automatically closed.

Signed at Pittsburgh, Penna., this 22nd day of February, 1913.
